UNITED STATES PATENT OFFICE.

CALVIN P. H. VARY AND HERMON D. HUTCHESON, OF NEWARK, NEW YORK.

POWER-TRANSMITTER.

SPECIFICATION forming part of Letters Patent No. 783,557, dated February 28, 1905.

Application filed December 9, 1903. Serial No. 184,370.

To all whom it may concern:

Be it known that we, CALVIN P. H. VARY and HERMON D. HUTCHESON, citizens of the United States, residing at Newark, Wayne county, New York, have invented certain new and useful Improvements in Power-Transmitters, of which the following is a full, clear, and exact description.

Our invention relates to power-transmitters, and more particularly to power-transmitters having means for speed regulation and means for reversing the same and also for throwing the same in and out of gear.

To that end our invention consists in the employment of the mechanism hereinafter described and illustrated; and in the description and illustration we have shown the same as applied to the driving mechanism of a motor-vehicle as a typical use of the same. Since, however, our invention is capable of much wider application, we do not wish to limit ourselves either to the particular use or to the particular construction herein shown and described, since from the description and illustration herein had a person skilled in the art may readily adapt the same to analogous uses or reform or modify the particular construction as the case may require. Furthermore, it will be readily understood that where it is desired to employ this invention with two motors, especially in a motor-vehicle, the same may be placed side by side and the mechanism herein described simply doubled up, the two motors running in reverse directions, each apparatus driving its respective wheel, and thus avoiding the necessity of a differential gearing.

We have also shown and shall claim certain attachments and improvements in connection with said main invention for operating a brake upon the driven mechanism when thrown out of operative contact with the driving mechanism.

Referring to the drawings herewith, Figure 1 is a side elevation of our invention. Fig. 2 is a plan view. Fig. 3 is a detail section on the line $\alpha\alpha$ of Fig. 2.

1 is a frame or base upon which the mechanism is mounted. This frame may be of any

desired form of construction so long as the same presents sufficient strength and rigidity.

2 is a motor mounted upon a frame 1, which is continuously driven and which has a continuously-driven fly-wheel 3. This fly-wheel 3 is provided with the friction-surface 4, which may be made of any desirable material.

5 is a disk or wheel mounted upon a shaft 6, which shaft is at right angles to the shaft carrying the fly-wheel 3, and said wheel 5 is so positioned as to be capable of engagement in frictional contact with the friction-surface of the wheel 3.

For the purpose of brevity we shall herein-after designate the wheel 3 and its friction-surface 4 as the "driving-disk" and the disk 5 as the "driven" disk.

The driven disk 5 is mounted slidably upon the shaft 6, which said shaft has a spline-groove 7, which engages a spline or feather within the hub of the disk 5. Upon the hub of the disk 5 is mounted a collar 8, within which the hub of said driven disk is free to rotate and by which it is held against axial movement in either direction. Secured to this collar by pivots is a bifurcated arm or yoke 9, which at its other end is mounted slidably upon a shaft 10. It will thus be seen that the driven disk 5 by the application of force to the yoke 9 may be carried over the length of the shaft 6, and consequently across the face of the driving-disk.

The shaft 6 is journaled in bearings 11 and 12. The bearing 11 is secured to the frame 1 by a single bolt 13, which acts as a pivot, as hereinafter more fully described. The bearing 12 is mounted upon the frame 1 by means of a bolt 14 taking through the slotted opening 15 in the base of said bearing. This slotted opening may be in the frame instead of in the base of the bearing, and to prevent any movement of the bearing except longitudinal movement the bearing may be held to the frame by guides or grooves. This bearing 12, therefore, is capable of longitudinal movement with reference to the length of the frame, and as the shaft 6 is mounted in these two bearings movement of the bearing

12 longitudinally upon the base or bed 1 will cause said shaft 6 to swing pivotally upon the pivot holding the bearing 11 in place. This therefore eventuates in throwing the driven 5 disk in and out of frictional contact with the driving-disk. Upon the outer end of the shaft 6 is mounted a sprocket 16 or other suitable means for transmitting the power from the said shaft to the wheel or other object to 10 be driven.

The bearings 11 and 12 are provided with 15 yokes, to which are pivoted arms 17 and 18. The other ends of the arms 17 and 18 are rigidly secured to the shaft 10, which is a hollow shaft and which contains within it the shaft 20 19 for the purpose hereinafter described. 20 is an arm also taking over the shaft 10 and at its opposite end is pivoted in a yoke of a block 21, which block is slidably secured to the 25 frame 1 by bolts 36 and 36' through slotted openings 22 in the base and the extension 24 of the base. This block 21 is held up to work by means of a compression-spring 23, which 30 thrusts in one direction against a bracket rigidly secured to the frame of the machine and at its other end thrusts against an adjustable bolt, engaging an L upon an extension 24 of the base of the block 21. The arms 17 and 18, pivoted to the bearings 11 and 12, are secured 35 on the shaft 10, and the arm 20, pivoted over the shaft 10 at one end and at the other to the block 21, constitute a toggle-joint, which when in its working position forms a brace to the sliding bearing 12 and yielding only 35 through the spring 23.

Mounted upon the shaft 19, which lies inside of the shaft 10, is a lever 25, which at its upper end may be provided with a handle for hand use or, as shown, with a plate to be 40 actuated by the foot and at its other end carries on a stud a roller 26, which treads upon the upper surface of the bed 1 and which is of the proper diameter to come in contact with the under side of the arm 18 when said 45 arm is in a horizontal position.

By referring now to the elevation of the drawings, it will be seen that when the lever 25 is thrown into the position indicated in broken or dotted outline the arms 17 and 18 50 and the arm 20 will be thrown into the position also shown in broken outline, and the driven disk will be withdrawn from contact with the driving-disk, as shown in dotted outline, thus throwing the machine out of gear. It will be noted that the swing of the arms 17 and 18 and the corresponding swing of the arm 20 will result in a very slight pivotal movement of the shaft 6, the driven disk, and the shaft 10 upon the pivot 13; but it will be at once understood that such movement being only a minute movement, just sufficient to throw the driven disk off from the face of the driving-disk, no cramping of the arms which take over the shaft 10 will 55 occur, since the ordinary freedom of a bear-

ing of this character is ample to permit of the necessary movement. It will also be seen that when the arms 17, 18, and 20 are thrown down into their normal working position, (shown in full outline) the thrust of the spring 70 23 will be quite sufficient, when properly adjusted, to hold the driven disk up to work with the driving-disk. The arms will be prevented from falling below a horizontal position by the roller 26, which treads on the 75 frame and which lies underneath the arm 18. This roller should be in diameter equal to the distance between the top of the frame 1 and under side of the arm 18 when said arm is parallel with the frame. It will also be especially noted that the sprocket 16 or other means of transmitting the power being placed outside of the pivot 13 the pull on chain or belt will further tend to swing the shaft 6 upon the pivot 13 and hold the driven disk up 80 to work with the driving-disk, and it will also be noted that as the driven disk is carried nearer the center of the driving-disk for the purpose of giving the motor greater leverage to carry a heavy load at a slower speed the 85 longer arm of the lever between the driven disk and the sprocket or pulley will be shortened, thus giving the pull on the chain or belt a greater leverage to hold the driven disk up to the driving-disk. 95

The arm 9 may be moved from side to side to increase or diminish the speed or reverse the direction of the driven disk by any desirable means. We have shown a simple method which is applicable to motor-vehicles, which 100 consists of a cable 27, which passes around sheaves 28 and 29, which are vertically pivoted to the frame 1 and which also passes around a drum 30, which is mounted upon a hollow shaft 31, which takes over the steering-post 105 32 and which carries at its upper end a hand-lever 33. The ends of the cable 27 are secured to the arm 9, and the cable is given one or more turns about the drum and centrally secured thereto to prevent slipping. It will 110 be evident that movement of the lever 33 will rotate the drum 30 and through the cable 27 will move the arm 9 in the direction desired. It will thus be seen that the change of speed is accomplished in the desired degree of quickness or slowness, and the progress from a slow speed to a high speed, or vice versa, or even to reverse, is accomplished without any jump or shock to the machinery. Any suitable locking device may be applied to lever 115 33 or drum 30 to keep it in position. 120

For the purpose of stopping the driven mechanism quickly, when it is desired so to do, we provide a brake connection which is actuated by the throw of the lever 25, secured to the end of the shaft 19, as clearly shown in Figs. 2 and 3. On the opposite end of the shaft 19 is mounted a crank 34, which will be rotated with the lever 25, as shown. This crank 34 carries a cable or chain 35, which 125 130

connects with a brake mechanism of any desired form. This cable is so adjusted as to slack that when the lever 25 is thrown into the position shown in dotted outline in Fig. 1 the crank 34 will not draw the cable 35 tight to set the brake. In this position, therefore, the driven mechanism will run free and the driving and driven disks will be out of contact. If now the lever 25 is thrown still farther forward, giving it a third position, this further throw will cause the crank 34 to draw on the cable 35 sufficiently to set the brake. In this manner a single short movement of the lever 25 throws the machine out of engagement with the driving mechanism, and a single long throw throws it out of engagement and sets the brake, or one short throw will disengage the driving mechanism, and a second throw will set the brake. This gives the operator a wide range of control through a single lever.

When it is desired to double up the mechanism and drive each of the rear wheels of a motor-wagon independently, the only change necessary from the construction shown in the drawings is to duplicate the mechanism herein shown. This does away with the necessity of the differential gear in the rear axle. If the motors are independent of each other, the friction-disks need not be disturbed in their contact position in turning corners. If they are connected, sufficient slip will occur to prevent the necessity of any device for disconnecting the inner wheel. It will also be understood that instead of the block 21 and the compression-spring 23 and the means described for connecting the same we may employ any other well-known method—as, for example, by making the arm 20 of two telescoping or sliding members and interposing therein a compression-spring to perform the same function. It will also be understood that we may employ instead of the pivot 13 and the sliding bearing 12 two sliding bearings or two hanging bearings and an additional arm 20, positioned to act substantially in line with the arm 17, thus giving the shaft 6 a uniform movement at right angles to its axis, and while we do not wish to limit ourselves to the pivotal construction shown and described we recommend the same as a preferable construction, for the reasons above set forth.

Having thus described our invention and its method of operation, what we claim is—

1. In combination with the frame of the machine, a driving-disk and a driven disk, a shaft carrying said driven disk, a bearing carrying one end of said shaft pivotally secured to the frame of the machine, a bearing carrying the other end of said shaft slidably secured to the frame of the machine, arms pivotally secured to said bearings, a shaft secured to the opposite ends of said arms, an arm for moving said driven disk axially, and mounted to slide on said last-mentioned shaft, an arm for mov-

ing said shaft carrying said driven disk, said arm being pivoted to said frame and to said shaft carrying the outer ends of said first-mentioned arms, whereby parallelism between the axis of the driven disk and the said last-mentioned shaft is at all times maintained. 70

2. In combination with a driving-disk and a driven disk means for moving the driven disk over the face of the driving-disk, a shaft carrying said driven disk, bearings carrying said shaft which carries said driven disk, one of said bearings being pivotally secured to the frame of the machine and the other mounted upon a guide on said frame which permits said shaft to swing in the plane of the axis of the driving-disk, an arm pivoted to said bearing, an arm pivoted to a rigid portion of the machine, a pivot engaging said arms, and means for moving said arms on said pivot, whereby the shaft carrying said driven disk is swung 80 on said pivoted bearing to throw said driven disk in and out of engagement with said driving-disk, substantially as and for the purposes set forth. 85

3. In combination with a driving-disk and a driven disk, means for moving the driven disk over the face of the driving-disk, a shaft carrying said driven disk, a sliding bearing on said shaft, an arm pivoted to said bearing, a pivoted bearing on said shaft, an arm pivoted to said bearing, an arm pivoted meditately to a rigid portion of the machine, a shaft engaging all of said arms to form a toggle-joint and means for moving said arms by a transverse movement of said last-mentioned shaft, whereby said first-mentioned shaft is swung on said pivoted bearing to throw said driven disk in and out of contact with said driving-disk, substantially as and for the purposes set forth. 90 100

4. In combination with a driving-disk and a driven disk, means for moving the driven disk over the face of the driving-disk, a shaft carrying said driven disk, a sliding bearing on said shaft, an arm pivoted to said bearing, a pivoted bearing on said shaft, an arm pivoted to said bearing, an arm pivoted meditately to a rigid portion of the machine, a shaft engaging all of said arms to form a toggle-joint, and a lever pivotally connected to said arms and having one end capable of engagement 110 with a rigid part of the machine and the other end manually operated, whereby said disks are thrown in and out of engagement, substantially as and for the purposes set forth. 115

5. In combination with a driving-disk and a driven disk, means for moving the driven disk over the face of the driving-disk, a shaft carrying said driven disk, a sliding bearing on said shaft, an arm pivoted to said bearing, an arm pivoted to said first-mentioned arm, a bearing or block pivotally secured to said last-mentioned arm and having a limited movement parallel to the movement of said sliding bearing, a bracket rigidly secured to a fixed portion of the machine, an interposed spring 120 125 130

for holding said bearing or block up to its work, and means for adjusting the force of said spring, substantially as and for the purposes set forth.

5 6. In combination with the frame of the machine, a driving-disk and a driven disk, a shaft carrying said driven disk, an arm for moving said shaft, an arm pivotally secured to said frame, a shaft pivotally engaging said arms to form a toggle-joint, a lever on said shaft, a crank on said shaft, and a brake-cable actuated by the movement of said lever moving said crank, substantially as and for the purposes set forth.

15 7. In combination with a driving-disk and a driven disk, means for regulating the speed of the driven disk, and means for throwing said disks in and out of engagement and means for releasing and setting a brake on the driven mechanism, comprising a toggle-joint for

throwing said driven disk in and out of engagement with said driving-disk, a shaft pivotally connecting the members of said toggle-joint, a lever secured to said shaft, and a roller on said lever for actuating said toggle-joint, a crank on said shaft, a chain or cable connecting said crank with a brake mechanism, said crank being positioned and said chain or cable adjusted to permit of the initial movement of said lever to throw said disks out of engagement, and the final movement of said lever acting to set the brake, substantially as and for the purposes set forth. 25 30

In witness whereof we have hereunto set our hands in the presence of two witnesses.
